UNITED STATES PATENT OFFICE

JOHN ALBERT PROCTOR, OF LEXINGTON, MASSACHUSETTS, ASSIGNOR, BY MESNE ASSIGNMENTS, TO GENERAL ELECTRIC COMPANY, A CORPORATION OF NEW YORK

HIGH POTENTIAL CONDENSER

Application filed December 4, 1928. Serial No. 323,592.

The subject of the present invention is a new and improved type of air-dielectric condenser for connecting signalling apparatus to a high tension power line, and a condenser especially valuable where a high tension power line is utilized for the transmission of signals as well as the transmission of power. Such a power transmission line may act as just described by impressing thereon a high frequency, low tension carrier current and modulating this carrier current with the desired signals.

An object of the invention is to provide a condenser of the kind indicated, which may be designed to have a capacity capable of transmitting the high frequency carrier current to the power line, while preventing passage of the low frequency, high tension power current and thereby protecting the signalling circuit and apparatus and the operators thereof from said power current; and which condenser, at the same time, may be constructed in such manner as to have a bulk distributed chiefly over an extended area in a substantially vertical plane, to incorporate exposed armature surfaces for various useful purposes.

Another object is to provide a condenser preferably of the kind last-described, of a very simple and comparatively inexpensive type, and of an adequately efficient and very rugged construction throughout.

Another object is to provide a condenser having exposed armature surfaces of the kind already indicated, adapted for convenient and practicable anchorage in various locations where such exposed armature surfaces may serve their intended purposes.

Still another object is to provide an air-dielectric condenser carrying armature surfaces exposed as more or less plane surfaces, and at the same time incorporating improved means for securing the condenser parts in proper relation while insulating the condenser from the ground both for the low frequency and the high frequency currents.

A condenser of the out-door type, for satisfactorily operating to couple a high tension power line with a signalling apparatus in a manner to protect the latter as required, may

be of considerable size. Such a condenser may be located adjacent to a travelled highway or otherwise before the eye of the public. In this regard, one of the concepts underlying the present invention is a condenser having its electrodes or armatures so shaped and arranged as to cooperate to provide an efficient condenser for the purpose intended, and at the same time a condenser incorporating, among other novel advantages, armature surfaces so conspicuous to the view as to warrant their utility as message-carriers over a considerable visual range. Thus, these surfaces, while functioning as working parts of the condenser, may be inscribed with warnings not to touch or come near the charged parts of the condenser, and/or general advertising matter carried, say, by bill-board sheets posted on said armature surfaces functioning as bulletin-boards or the like.

In carrying out the invention, there may desirably be employed a plurality of air-separated substantially vertical steel or other suitable metal sheets or walls constituting the armatures, and so disposed that one or more of these sheets may act as bill-boards or surfaces for carrying messages, as above, and also as natural and quick rain-water shedders.

A construction now preferred, and the one illustrated, by way of example, in the accompanying drawings, includes an armature, to be connected to the power line, which is in the form of a slenderized inverted U straddling a plane wall or plate armature to be connected to the signalling circuit; thereby to provide a condenser having three substantially flat plates, two of which are the legs of the inverted U. These two outer plates, charged with the high tension current, will be the more exposed ones; an apparent disadvantage more than offset by the advantage of having them available as warning-carriers and bill-boards, as above described.

The invention consists in features of construction and combinations of parts as hereinafter set forth and claimed.

The following description of the embodiment at present preferred will make the invention more clearly understood; but such description is to be taken in an illustrative

and not in a delimiting sense, except as features of the invention are particularly specified by the claims.

Said preferred embodiment is shown in the accompanying drawings, in which

Fig. 1 is a side elevation;

Fig. 2 is an end elevation; and

Fig. 3 is an enlarged detail showing a modification, being a fragmentary sectional view as though taken on line 3—3 of Fig. 1.

Similar reference characters refer to similar parts throughout the several views of the drawing.

Referring to Figs. 1 and 2, the armature 4 for connection in any suitable way to the signalling circuit may be a rectangular metal plate arranged in a vertical plane and rather considerably elongated horizontally.

The armature for connection in any suitable way to the power line may also be a rectangular metal plate, 5, bent into an inverted U-shape, to include, in effect, two armature plates 5' and 5'' (parallel to each other and to the armature 4 interposed therebetween, and equidistant from said armature 4), and an intermediate curved portion 5A forming the bowl of the inverted U defined by armature 5 in cross-section.

This curved portion 5A of armature 5 may also have a capacity action with armature 4, due to the cylindrical structure 4A at the top of armature 4 which is desirably present; and which structure 4A is here shown as the upper marginal portion of plate 4 rolled over circularly on itself along the length of plate 4.

This cylindrical structure 4A may also be useful to further stiffen the armature 4 to its flat-plate condition, as may also a similar cylindrical structure 4B which may be formed at the bottom of armature 4.

In the construction illustrated, these structures 4A and 4B at top and bottom of armature 4 are additionally useful in facilitating the incorporation of simple yet rugged hanger means at opposite ends of the armature 4.

Such hanger means, at each end of the armature 4, may include a metal brace and guy strap 6, bent from say, steel bar-stock to an inverted V form, with an eye-enlargement 6A at the apex of the V; and a cradle-strap 7, bent from similar bar-stock to have a half-round depression 7A midway of its ends.

When these parts are set up as shown in the drawings, the cylindrical structure 4A of armature 4, at a point near each end of the armature, is embraced by the eye-enlargement 6A of a strap 6, and the cylindrical structure 4B of armature 4, at a point near each end of the armature, is seated well within the depression 7A in a strap 7.

The straps 6 and 7, where coupled to armature 4, as just described, are desirably welded thereto, to which end the armature 4 may advantageously be made of sheet steel.

The positioning of the straps 6 and 7 relative to armature 4 is desirably such as to locate a pair of straps 6 and 7 at each end of the armature, with a strap 7 vertically below a strap 6, so that the terminal portions of both straps, as indicated at F (where strap 6 is shown as having suitably offset foot-portions to extend horizontally with strap 7), may be brought together to align four pairs of openings (not shown), one in each of the two trap-ends at the four F locations. These aligned pairs of openings may receive the shanks of bolts 8 or the like, each suitably secured in one of four insulators 9 arranged at the four basal corners of the condenser, where blocks 10, of concrete or the like, may be provided to carry said insulators.

Between these blocks 10 may be other and larger blocks 11 of concrete or the like, as illustrated. These blocks 11 may be elongated transversely of the condenser, so that each may support a pair of insulators 12, near the opposite ends of armature 5, and on which insulators 12 said armature 5 may be mounted.

The securing means for the armature 5 may comprise securing elements solely for the lower portions of said armature. This is so, because the U-shape of the armature 5 may be relied on to act as a self-stiffener for the same, to insure that when such securing elements are employed the armatures 4 and 5 will be permanently rigidified in their predetermined spacings to maintain constant the air-dielectric capacity as originally calculated. Said securing means for the lower marginal portions of the armature 5 may in part be provided, and made rigidifying functioning, by curling such marginal portions circularly outwardly to form troughs as indicated at 5B. This is a preferred construction, as a rigidifying means particularly, because then the sheet metal of which armature 5 is made may be fairly thin as compared to its superficial area. With an insulator 12 each underlying a trough 5B of armature 5 near an opposite end of such trough, as illustrated, a bolt 14 or the like may be passed down through a washer 15 (having a convexly rounded bottom shaped to conform nicely to the concavity of the trough interior), and through a suitable aperture (not shown) in said trough, and thence through a flat-bottomed washer 16 (underlying the trough 5B and having a concavely rounded top shaped to conform nicely to the convexity of the trough exterior), and finally suitably secured inside each of the insulators 12, to anchor the armature 5 in place as intended.

Referring to Fig. 3, where the parts shown correspond to the like numbered parts in Figs. 1 and 2, this illustrates a simple and inexpensive method of further rigidifying the inner armature 4, as by welding a thin-walled tube or pipe 17, which may be co-extensive in length with the armature 4, in-

side the upper marginal rolled-over portion 4A thereof. A similar pipe (not shown) may be similarly associated with the lower marginal rolled-over portion 4B of said armature 4. 5 A comparatively large radius of curvature for the rolls or curled portions 4A and 4B or armature 4, and 5A and 5B of armature 5, is preferably incorporated to combat concentrations of electrostatic stresses and minimize if not avoid undesirable corona effects. 10

The areas, overlappings and spacings of the armatures 4 and 5 will be governed by the voltages to which the condenser is to be subjected, due regard being had to the air 15 dielectric employed. As a specific example, a condenser for subjection to 33 to 44 k. v., and having a capacity of .0013 m. f. d., should, with a three inch separation between armatures 4 and 5, have about 100 square feet of 20 dielectric surface, which could be obtained in the condenser illustrated in the drawing, by making the armature 5, as to that portion of it viewed in Fig. 1, approximately five feet high and ten feet long.

25 A condenser of the type exemplified by the specific embodiment shown in the accompanying drawings, is adapted to permit passage of a high frequency current to the high tension power line, while preventing the power 30 current to be applied to the carrier-current-impressing line. Such new condenser, moreover, may be supported on an inexpensive foundation, and a ground-level one where desired, and also on low-cost yet dependable

35 insulators assuring proper protection against break-down due to grounds. The new condenser, further, may be characterized by a bulk, simply yet rigidly established, distributed chiefly in a substantially vertical plane, 40 for carrying, conspicuously, warning or other useful messages or indicia. It will readily be seen that such a condenser naturally provides a pair of oppositely facing billboard- or bulletin surfaces, to wit, the outer 45 faces of plate portions 5' and 5" of armature 5, adapted to carry warnings and announcements capable of being observed and taken cognizance of, at considerable distances. Both armatures 4 and 5, because entirely or

50 in the main characterized by a bulk distributed in substantially a vertical plane, act as natural water shedders; while, if the inverted U-shape for armature 5 be retained, there is an additional protection for the inner surfaces of plate portions 5' and 5" of 55 said armature, as well also as additional protection for the opposite faces of armature 4.

Consequently, the invention provides a 60 novel type of condenser well-adapted for out-door use, particularly in locations near popular travel-lanes; and a condenser at the same time calculated to attain all the other objects and incorporate all the other advantages already pointed out.

65 The dimensional and other qualitative data

set forth hereinabove in regard to the particular condenser illustrated in the drawings, it will be understood, are not to be taken as in any way delimiting the invention; and the same is to be understood as to various structural changes possible, and falling within the spirit of the invention as defined by the claims following.

I claim:

1. A high-voltage condenser for the purpose described, comprising armatures one of which is an outer sheet structure and another of which is an inner sheet structure, with an air dielectric between, the outer sheet structure having an arched central portion roofing an upper edge portion of the inner sheet structure and also arched lower portions forming longitudinal troughs on opposite sides of the condenser. 75

2. A high-voltage condenser for the purpose described, comprising an inner armature including a substantially vertical sheet-structure, and an outer armature including a plurality of substantially vertical sheet-structures, said armatures carrying curved portions extending longitudinally and acting as stiffeners for such sheet-structures, said curved portions being of sufficient radius to avoid excessive concentrations of electrostatic stresses thereat. 80

3. In a high-voltage condenser for the purpose described, an armature comprising in the main an upright wall-structure, said armature having along its upper edge a substantially cylindrical enlargement and along its bottom edge a substantially cylindrical enlargement. 90

4. In a high-voltage condenser for the purpose described, an armature comprising in the main an upright substantially plane wall having enlargements near its top and bottom, hanger means for positioning said armature upright, said hanger means including a cradle strap shaped to receive and seat said bottom enlargement and also including a bracing strap shaped to receive and seat said top enlargement. 105

5. In a high-voltage condenser for the purpose described, an armature comprising in the main an upright substantially plane wall having enlargements at its top and bottom, and means for mounting said armature including a plurality of straps for engaging and holding said enlargements one above the other as predetermined, one of said straps being V-shaped and engaging one of said enlargements near the apex of the V. 115

6. An air-dielectric high-voltage condenser for the purpose described, comprising armatures one of which is an armature of substantially inverted U-shape having its bulk principally distributed through a substantially vertical plane, said armature having outwardly bent lower portions on opposite sides thereof, an insulated mounting struc- 125

130

ture for said armature, and means for conformingly seizing said bent portions and for permanently positioning said armature on said mounting structure.

- 5 7. In a high-voltage condenser for the purpose described, an armature including a substantially plane wall structure, and a hanger means for securing said wall-structure at a predetermined angle to the horizontal, said
10 hanger means including four shaped straps and four insulation-protected anchorages for the eight terminal portions of said four straps.

8. In a condenser for the purpose described, the combination of a first armature including in the main a substantially vertical wall and having a curvilinear enlargement at its upper portion and a curvilinear enlargement at its lower portion; a second armature
20 having a curvilinear central portion roofing over the curvilinear upper portion of the first armature, skirt portions depending from said central portion and constituting walls lying substantially parallel with and alongside of the wall of the first armature, and curvilinear terminal portions at the bottoms of said skirt portions; all said curvilinear portions constituting stiffening agents for said walls; and mounting and insulating
25 means for the armatures engaging a plurality of said curvilinear portions of both armatures and coacting with said curvilinear portions to maintain said armatures in proper assembly.

- 30 9. In an air-dielectric condenser for the purpose described, the combination of a first armature including in the main a substantially vertical wall and having a curvilinear enlargement at its upper portion and a curvilinear enlargement at its lower portion; a second armature having a curvilinear central portion roofing over the curvilinear upper portion of the first armature, skirt portions depending from said central portion and constituting walls lying substantially parallel with and alongside of the wall of the first armature, and curvilinear terminal portions at the bottoms of said skirt portions; said curvilinear portions in part forming stiffening agents for said walls, and in part forming means for assembling and anchoring the working parts of the condenser in predetermined relation; such assembling and anchoring means including two groups of insulators, means for conformingly seizing the curvilinear portions of one of said armatures and mounting that armature atop one of said groups, and means including a strap-structure of substantially inverted-V shape and
55 60 a coacting underlying cradling strap-structure, for conformingly seizing the curvilinear portions of the other armature and mounting that armature on the other of said groups.

- 65 10. A condenser comprising electrically

connected outer plates constituting one armature, an intermediate plate of different length from said outer plates and constituting an armature of opposite polarity, said intermediate plate projecting beyond the ends of the outer plates and insulating supporting means for each armature, said supporting means for the intermediate armature being spaced longitudinally with respect to the insulating supporting means for the outer armature. 70 75

In testimony whereof I hereunto affix my signature.

JOHN ALBERT PROCTOR.
